US00D825190S

(12) **United States Design Patent** (10) **Patent No.:** **US D825,190 S**
Hu (45) **Date of Patent:** **** Aug. 14, 2018**

(54) **POWER SCRUBBER**

(71) Applicants: **Suzhou KVC Electric Co., Ltd,**
Jiangsu (CN); MPOW
TECHNOLOGY CO.,LIMITED,
Hong Kong (HK)

(72) Inventor: **Zaihui Hu**, Shenzhen (CN)

(73) Assignees: **Suzhou KVC Electric Co., Ltd,**
Jiangsu (CN); MPOW
TECHNOLOGY CO., LIMITED,
Hong Kong (HK)

(**) Term: **15 Years**

(21) Appl. No.: **29/641,587**

(22) Filed: **Mar. 23, 2018**

(51) LOC (11) Cl. **04-02**

(52) U.S. Cl.

USPC **D4/102**

(58) **Field of Classification Search**

USPC D32/15, 17, 19, 20, 25, 40, 45, 50, 51;
D4/100, 102, 109, 110, 111, 127, 199

CPC A47L 11/202

(57) **CLAIM**

The ornamental design for a power scrubber, as shown and described.

DESCRIPTION

FIG. 1 is a perspective view of a power scrubber showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a perspective view thereof with the lower part rotated; and,

FIG. 9 is an exploded view thereof.

The dashed broken lines illustrate portions of the power scrubber and form no part of the claimed design.

1 Claim, 6 Drawing Sheets
